Primary Examiner—Susan J. Lucas*Assistant Examiner*—Jennifer A. Regester[57] **CLAIM**

The ornamental design for an ironing board, as shown.

DESCRIPTION

FIG. 1 is a top plan view of an ironing board of my new design;

FIG. 2 is a bottom view thereof;

FIG. 3 is a side perspective view thereof with the legs erected;

FIG. 4 is a side elevational view thereof; the opposite side being a mirror image thereof;

FIG. 5 is an end elevational view thereof; and,

FIG. 6 is an elevational view of the opposite end thereof. The broken lines are shown for illustrative purposes only and form no part of the claimed design.
